UNITED STATES PATENT OFFICE

127,820

DESIGN FOR A JAR OR SIMILAR ARTICLE

Virginius A. Tomasson, East Orange, N. J., assignor to Armstrong Cork Company, Lancaster, Pa., a corporation of Pennsylvania

Application April 3, 1941, Serial No. 109,114

Term of patent 14 years

To all whom it may concern:

Be it known that I, Virginius A. Tomasson, a citizen of the United States, residing in East Orange, county of Essex and State of New Jersey, have invented a new, original, and ornamental Design for a Jar or Similar Article, of which the following is a specification, reference being had to the accompanying drawing, forming a part thereof, and of which

Figure 1 is a view in front elevation of a jar or similar article, showing my new design;

Figure 2 is a view in side elevation thereof; Figure 3 is a sectional view taken on line III—III of Figure 1; and

Figure 4 is a bottom plan view.

The characteristic features of my design reside in the portions shown in full lines.

I claim:

The ornamental design for a jar or similar article, substantially as shown and described.

VIRGINIUS A. TOMASSON.
